AUTOMATIC SCALE REMOVER

Filed Aug. 14, 1943

UNITED STATES PATENT OFFICE

2,466,644

AUTOMATIC SCALE REMOVER

John J. McBride, Bayonne, N. J., assignor to
American Car and Foundry Company, New
York, N. Y., a corporation of New Jersey

Application August 14, 1943, Serial No. 498,720

3 Claims. (Cl. 29—81)

1

This invention relates to scale removers in general and in particular to scale removers of the automatic type for use in connection with metal working rolls.

In all working of hot metal considerable scale is encountered and it is necessary that this scale be removed, particularly where the article being molded, worked or pressure welded is intended for use as a container for materials which must remain uncontaminated. It is an object, therefore, of the present invention to provide a scale remover of the automatic type adapted for use with a pressure welding machine.

A further object of the invention is the provision of a scale remover automatically swung into position by pressure of the rolls on the material being worked.

A still further object of the invention is the provision of a scale remover automatically brought into position by movement of one of the rolls in its bearings.

These and other objects of the invention will be apparent to persons skilled in the art from a study of the following description and accompanying drawings, in which

Fig. 1 is an elevational view of the improved welder with the automatic descaler applied thereto;

Fig. 2 is an enlarged elevational view of the improved scale remover;

Fig. 3 is an end view of the device, and

Fig. 4 is an elevational view similar to Fig. 2 but showing the position of the parts when the scale remover is out of contact with the work.

Referring now to the drawings in detail, it will be seen that the welding machine M is formed with an upper jaw 2 and a lower jaw 4 so formed as to provide a relatively long and narrow gap therebetween for reception of the work W. As clearly shown in Fig. 1 the upper jaw 2 carries at its extremity a roller 6 rotatably mounted on an axle 8 which in turn is carried by a vertical reciprocable member 10. The upper end of the reciprocating member is provided with a piston 12 working in a cylinder 14 supplied by a fluid under pressure through line 16. A spring 18 surrounds the reciprocating member or piston rod and is of sufficient strength to lift the entire assembly, thereby normally holding the pressure roller 6 in a lifted position. Immediately beneath the pressure roller 6 is a second pressure roller 20 carried at the outer end of the lower jaw 4. This lower pressure roller is mounted upon an axle 22 carried in bearings 24, which bearings are vertically elongated as at 26 and clearly shown in Figs.

2

2 and 4. The construction just described is of more or less conventional form with the exception of the elongated bearings for the lower pressure roller.

5 In order to apply the automatic scale remover to the welding machine the lower arm 4 is drilled and tapped to receive pivot bolts 30 located outwardly of the axle 22. Pivotal mounted on pivots 30 are side arms 32 formed adjacent the 10 pivotal mount with openings 34 for reception of the ends of axle 22. Adjacent these openings spring seats 36 are formed on the side arms and buttressed to the side arms by ribs 38. In order to clear the lower jaw 4 the side arms are offset 15 inwardly as at 40, then extended outwardly as at 42 to provide supports for a descaling brush 44. This brush is carried on a rod 46 extending through the ends 42 of the side arms and locked in position against rotation by pins 48 extending 20 through the rod and through slots 50 formed in the end portions 42. In this manner by removal of the pins the brush holding rod may be turned and pins reinserted to bring a new portion of the brush 44 into position for contact with the work. 25 It is obvious that this brush is only one form of a tool for removing scale from the work and that various other forms of tools such as scrapers, fluted rollers, etc., may be substituted for the stationary brush shown. Immediately beneath 30 the bearings for axle 22 bracket members 60 are secured to the jaw 4 by bolts 62. Each of the brackets is formed with a spring seat 64 buttressed to the securing portion of the bracket by ribs 66. Springs 70 are interposed between and bear upon 35 spring seats 36 and 64 and these springs are of sufficient strength as to normally lift the pressure roller 20 together with its axle and hold the same at the upper end of the elongated bearings 24.

The operation of the device is as follows and 40 assuming the parts in the unloaded position which they assume and as shown in Fig. 4: The heated work W is placed upon the pressure roller 20 and fluid under pressure admitted to cylinder 14, thus forcing the top or movable pressure roller 6 45 downwardly onto the work. This pressure which is sufficient to roll the heated work metal will force the lower or supporting roller 20 downwardly in its elongated bearings 24. Downward movement of the supporting roller, together with 50 its axle, will cause rotation of the side arms about the pivots 30 compressing springs 70 and bringing the brush or scraping tool 44 into bearing with the work as clearly shown in Fig. 2. Relative motion between the machine and work will cause the 55 scraping tool or brush 44 to remove the scale from

the work before the work passes through the rollers 6 and 20 thereby preventing the rolling of scale into the metal on the interior or under side of the work as shown in Fig. 2. Upon removal of fluid pressure from cylinder 14 the spring 18 will lift the roller 6 and springs 70 can then lift the supporting roller 20 and rotate the side arms to the position shown in Fig. 4 in which the scraping tool or brush 44 is out of contact with the work.

While the scale remover has been shown and described as applied to a pressure welding machine, it will be obvious that it may be applied to any machine utilizing rollers or pressure devices for working metal. Furthermore, although the descaler has been shown as applied to only the supporting roller thereby descaling only one side of the work, it will be obvious that a similar arrangement can be applied to the top roller supporting frame, thereby descaling both sides of the work. Although the construction has been described more or less in detail, it will be likewise obvious that various modifications and rearrangements of parts other than those shown and described may be made and all such modifications and rearrangements of parts are contemplated as fall within the scope of the following claims defining my invention.

What is claimed is:

1. A scale remover for work comprising in combination, a frame, elongated bearings carried by the frame, an axle mounted in said bearings for translational movement, a work supporting roller mounted on said axle, side arms pivotally mounted on said frame adjacent said axle and having portions engaging said axle whereby translational movement of the axle in said elongated bearing will cause swinging movement of the side arms about their pivotal mount, a scale removing device carried by said side arms and movable therewith into and out of engagement with the work during swinging movement of the side arms, resilient means urging said axle toward one side of said elongated bearings to thereby normally hold said scale removing device out of engagement with the work, and a pressure roll carried by said frame and movable toward the work supporting roller to thereby grip the work, said pressure roll forcing said axle toward the other side of the elongated bearings and swinging the scale removing device into engagement with the work.

2. A scale remover for work comprising in combination, a frame, spaced pairs of superimposed elongated bearings carried by the frame, an axle shiftably mounted in each pair of elongated bearings for movement towards and from each other,

a work supporting roll carried by one axle, a pressure roll carried by the other axle, side arms pivotally mounted on said frame adjacent one axle and having their inner end portions engaging said axle whereby movement of said axle in said elongated bearings will cause swinging movement of said arms on their pivots, a scale removing device carried at the free ends of said arms and movable therewith into and out of engagement with the work with the swinging movement of said arms, said arms being formed with laterally offset recesses, spring members having one end portion engaging a portion of the frame and the other end portions received in said recesses to normally urge said scale removing device downwardly and the associated roll upwardly, and power means for moving the pressure roll toward said supporting roll to shift the latter in its bearings against the said springs.

3. A scale remover for work comprising in combination, a frame, spaced pairs of superimposed elongated bearings carried by the frame, an axle shiftably mounted in each pair of elongated bearings for movement towards and from each other, a work supporting roll carried by the lower axle, a pressure roll carried by the upper axle, side arms pivotally mounted on said frame adjacent said lower axle and having portions engaging said axle whereby movement thereof in its elongated bearings will cause swinging movement of said arms on their pivots, a scale removing device carried at the free ends of said arms and movable therewith into and out of engagement with the work during swinging movement of said arms, spring means urging the work supporting roll toward the pressure roll, and power means for moving the pressure roll toward said supporting roll to shift the latter in its bearings against said springs.
